UNITED STATES PATENT OFFICE.

J. B. OKEY, OF INDIANAPOLIS, INDIANA, ASSIGNOR TO HIMSELF, AND W. Y. WILEY, OF MARION COUNTY, INDIANA.

STRAW-CUTTER.

Specification of Letters Patent No. 19,895, dated April 6, 1858.

To all whom it may concern:

Be it known that I, JOSEPH B. OKEY, of Indianapolis, county of Marion, and State of Indiana, have invented a new and useful

5 Improvement in Straw-Cutting Machines; and I do hereby declare that the following is a full and exact description thereof, reference being had to the accompanying drawings and the letters of reference marked

10 thereon.

Figure 1, is a perspective view showing the general appearance of the machine. Fig. 2 is a sectional end view showing the arrangement of the adjustable gage G and

15 knives F, F. A is a double feed box. B a drum or wheel. C a slot for the screw D to operate through.

G, is a gage plate. 20 F, F, are knives or cutters.

The following is the operation of the machine: The straw being placed in the box A is fed by its own weight. Falling upon

the gage plate G it slides upon the same until cut off by the knives F F at each revolution of the drum B which is revolved by the crank E. 25

D is a thumb screw by which the gage G is held when adjusted in the slot C by moving it to or from the center thus making 30 the cut long or short as may be desired.

Fig. 3 is a section showing the knives upon the drum B.

What I claim and desire to secure by Letters Patent is— 35

The combination and arrangement of the box A, gage G, knives F, F, or their equivalents upon the drum or wheel B when constructed and arranged substantially as set forth.

JOSEPH B. ^{his} OKEY.
